UNITED STATES PATENT OFFICE.

HERMAN GEORGE SCHUETTE, OF MANITOWOC, WISCONSIN.

CANOPY-SUPPORT FOR BEDS.

SPECIFICATION forming part of Letters Patent No. 739,352, dated September 22, 1903.

Application filed December 3, 1902. Serial No. 133,689. (No model.)

To all whom it may concern:

Be it known that I, HERMAN GEORGE SCHUETTE, a citizen of the United States, residing at Manitowoc, in the county of Manitowoc and State of Wisconsin, have invented certain new and useful Improvements in Canopy-Supports for Beds, of which the following is a specification.

My invention relates to improvements in metal beds of that class in which vertical hollow corner-posts are used; and the object of my improvements is to provide extensible means on such corner-posts on which may be supported a mosquito-canopy, curtains, or other draperies to exclude drafts of air and which will afford a convenient place to hang the pillow shams or covers which are commonly used.

In carrying out my invention I have provided an attachment for the common iron or brass corner-posts which is adapted to slide within the post and to be extended therefrom vertically to a predetermined height and which when in its normal position within the post does not alter the appearance of the latter in the least.

The details of my invention are fully illustrated in the accompanying drawings, which form a part of this application for patent, and in which—

Figure 1 is a perspective view of a bed equipped with my invention, the latter supporting a mosquito-canopy. Fig. 2 is a detail, on an enlarged scale, partly in section and partly in elevation, of one corner-post to which is applied the extensible rod forming a part of my invention. Fig. 3 is a cross-section through the post and rod, showing their relative positions when the rod is being drawn out of the post; and Fig. 4 is a view similar to Fig. 3, but showing the rod in its extended position and at rest.

Referring to the figures of the drawings, A represents the usual hollow vertical metal bedposts at each corner of the bed. Just below the upper edge of each post is fixed a ring a' , at one point in which is cut a square notch a^2 , that opens into or extends from the bore of the ring. Near the lower end of the post a pin a^3 is fixed in suitable holes in opposite sides of the post, thus extending across the bore of the post for a purpose to be here-

inafter stated. Arranged within the post is a tube (a solid rod may be used, if desired) b , to the upper end of which is attached in any suitable manner the knob b' , which is of the usual construction. To the lower end of the tube is secured a circular plate b^2 , the diameter of which is slightly less than that of the bore of the post, so that it may freely slide within the latter, but without appreciable lateral movement or play. At a point a short distance above the plate b^2 is a lug b^3 , which extends at right angles from the tube. The diameter of this lug is slightly less than the diameter of the notch a^2 , so that when it is brought to register with said notch and the tube lifted the lug will pass through the latter. It will be noted that the cross-diameter of the tube is such that it may slide easily through the opening in the center of the ring and that the latter, together with the plate b^2 , will guide and maintain the tube in its vertical relation to the post, whether it be in its extensible position or in its normal position. It will also be apparent that when the lug b^3 has been drawn through the notch a^2 and the tube given a slight turn the lug will be brought over the plate or ring a' , and thus the tube will be prevented from dropping by gravity back into the post and will therefore be held in its extended position.

To the lower portion of the knob is secured a collar b^4 , in which an annular groove is provided to receive a cast ring c' , in which is fixed the end of the cross-rod C, which connects the two posts of the head and foot of the bed, respectively. When the knob is lifted up, the collar b^4 will be drawn up with it, and also the ring c' , which is carried on the collar and the cross-rod C, the end of which is fixed in the ring. By grasping the rod at or near a point half-way between two opposed posts I may lift two tubes simultaneously, and as the lugs on the tubes are brought in registry with the notches in the rings a' the tubes are partially rotated, as heretofore described.

It will be apparent that the elevation of the tubes alone will furnish a suitable support for a mosquito-canopy, and in some cases I may therefore dispense with raising the cross-bar.

The cross-bar at the head of the bed is especially convenient for holding the pillow.

shams when it is raised out of the way and the said covers are not in use, and it may be exclusively used for that purpose.

While I have shown the use of the cross-bar 5 that is now commonly employed in metal beds, I may employ a supplemental cross-bar especially adapted to the uses stated.

It will be noted that the joint between the knob and the post is entirely concealed when 10 the tube is within the post by the skirt or lower portion of the knob, so that to all external appearances the bedpost is of the ordinary character, thus relieving it of the objections inherent in a construction for a similar purpose in which the extensible rod is on 15 the outside of the post.

I have shown but one lug in the side of the tube; but it is manifest that several such lugs may be fixed at different heights in the 20 tube, and thus provide for adjusting the tubes at different elevations relative to the posts. The pin α^3 limits the downward movement of the tube.

I am aware that extensible rods have been 25 applied to bedposts as a means of supporting mosquito-canopies, and I do not broadly claim such devices; but

What I claim as new, and desire to obtain by Letters Patent, is—

30 1. In combination with a hollow bedpost having a notched collar in its upper end, a tube adapted to slide within the post and to be rotated therein, said tube carrying a knob at its upper end, and provided with a lug 35 near its lower end, said lug adapted to pass

through the notch in said collar, and to rest on the upper side of the collar when the tube is partially rotated, substantially as set forth.

2. In combination with two oppositely-arranged hollow bedposts, each having a notched 40 collar in its upper end, tubes slidably and rotatably mounted in said posts, said tubes having lugs thereon, said lugs adapted to pass through the notches in said ring, a knob secured to the upper end of each of said tubes 45 and having a portion loosely encircling the post, a collar loosely mounted on said portion of the knob, and a cross-rod having its ends secured in the said collars of the opposed posts, substantially as set forth.

50 3. As a means for supporting a mosquito-canopy or the like, in combination with a hollow bedpost, a notched ring secured within the post near its upper end, and a stop secured in the lower portion of the post, a tube 55 slidably and rotatably mounted in said post, and passing through said ring, said tube having lugs extending radially from its side, said lugs adapted to pass through the notches in said ring, and also having a guide-plate secured to its lower end, and a knob secured to its upper end, all substantially in the manner and for the purpose set forth.

In testimony whereof I affix my signature in presence of two witnesses.

HERMAN GEORGE SCHUETTE.
